UNITED STATES PATENT OFFICE.

GEORGE W. NAGEL, OF CHICAGO, ILLINOIS, ASSIGNOR OF ONE-THIRD TO WILLIAM L. NEWMAN, JR., AND ONE-THIRD TO CHARLES F. BLISS, BOTH OF CHICAGO, ILLINOIS.

METHOD OF REMOVING OILS, FATS, AND GREASES FROM CLOTHS, AND APPARATUS.

Specification of Letters Patent. Patented Feb. 12, 1918.

1,256,356.

Application filed February 8, 1917. Serial No. 147,481.

To all whom it may concern:

Be it known that I, GEORGE W. NAGEL, a citizen of the United States, residing at Chicago, in the county of Cook and State 5 of Illinois, have invented certain new and useful Improvements in the Methods of Removing Oils, Fats, and Greases from Cloths, and Apparatus, of which the following is a specification.

10 My invention relates to the operation of removing or extracting oils, fats or greases from cloth, or similar material, recovering the extracted matter and cleansing the cloths.

15 The principal object of the invention is to provide a simple, convenient and economical method for accomplishing this operation.

20 A further object is to provide an improved apparatus for the extraction of oils, fats or greases from materials containing such substances, and more particularly to provide an apparatus suitable for carrying out the method of removing these substances 25 from cloths for the purpose of recovering the oil or fatty matter and cleansing the cloths.

It has been the custom in the manufacture 30 of oleomargarin to wash the press cloths for the purpose of recovering the fatty matters with which they have become permeated, the fat recovered being used again in the manufacture of the oleomargarin product. It has been the usual practice to boil 35 the cloths in distilled water (distilled water being used for sanitary reasons) and skim off the fats as they rise to the surface of the water. It is necessary, ordinarily, to subject the cloths to several such boiling

40 operations. In the last operation caustic soda is put into the water so as to cleanse the cloths, the butterine fats washed out in this operation being, therefore, wasted.

45 This washing operation is expensive and tedious and the vats used take up considerable space. After the cloths have been washed they are hung out to dry and this requires additional space in the factory besides involving time and labor. My invention provides a radically different method 50 for recovering fatty matter and cleansing the cloths. This method has the advantage of economy and the recovery of practically

all of the fatty matter, and can be carried out by a simple, inexpensive and compact 55 apparatus.

The process, as will be understood, is not limited to the treatment of oleomargarin press cloths but might be employed for the treatment of any cloths, rags or similar material (the word "cloths" being used generically in this connection) which are saturated with any oil, fat or grease.

The improved method will be described in connection with the accompanying drawing which shows, in vertical sectional elevation, an improved form of extracting apparatus suitable for the purpose.

Referring to the drawing, 1 is a casing supported on a suitable stand 2. 3 is a 70 revoluble container arranged within the casing 1 and supported on a shaft 4 having a pulley 5 by means of which the shaft may be driven by a belt (not shown). The casing is provided with a discharge opening 6 75 from which a pipe 7 leads to a vessel 8 adapted to receive the oil, fat or grease recovered from the extracting process. The side wall of the container 3 is formed with perforations 9. The top of the container 80 is open, as indicated at 10, and the casing 1 is provided with a corresponding opening closed during the operation of the machine by a cover 11. In the annular space 12, between casing 1 and the container 3, is arranged a steam coil 13 formed with perforations 14 arranged to direct jets of steam 85 against the side wall of the container. Steam is supplied to the coil by a pipe 15 which extends through the discharge opening 6. 90

The cloths, or other like material, are placed in the container 3 and the container is revolved at relatively high speed. At the same time steam is introduced into casing 1 through the steam coil 13. The combined 95 effect of centrifugal force and of the heat supplied by the steam is to produce a complete extraction of the oil, grease or fat from the cloths, the extracted substances passing through opening 6 and pipe 7 (with 100 the water from the condensation of the steam) into vessel 8 from which the oily or fatty matter may be skimmed or removed in any desired manner.

Preferably steam is introduced into the 105 steam coil under considerable pressure.

It will be understood that, so far as the method is concerned, it is not to be considered as limited to the particular type of apparatus shown and described. So far as concerns the apparatus, it might be modified in certain unessential respects without departure from the invention expressed in the claims.

I claim:

- 10 1. The method of removing oils, fats or greases from cloths which consists in subjecting the cloths to centrifugal force against a retaining element and at the same

time applying jets of steam to the opposite side of said element.

- 15 2. Extracting apparatus comprising a revoluble container having perforations in its side wall, an inclosing casing for the container having a discharge outlet, a steam coil in the casing surrounding the container having perforations to direct jets of steam against the side wall of the container, and a supply connection for the steam coil extending through said discharge outlet.

GEORGE W. NAGEL.
